COMBINED CHEESE BOARD AND CUTTER

Jens H. Quistgaard, Copenhagen, Denmark, assignor to Dansk Designs Inc., Great Neck, N. Y.

Application May 19, 1958, Serial No. 50,955

Term of patent 14 years

(Cl. D44—1)

Fig. 1 is a plan view of the combined cheese board and cutter, showing my new design; and

Fig. 2 is a side elevation thereof.

I claim:

The ornamental design for a combined cheese board and cutter, substantially as shown.
